UNITED STATES PATENT OFFICE

GEORGE ERNEST STROUP, OF HOMER TOWNSHIP, OHIO

HAY LOADER

Application filed May 18, 1927. Serial No. 192 302.

My invention particularly relates to hay-loading means whereby the hay is loaded in sections or portions of a complete load upon the rear of the wagon or other carrier, is uniformly packed laterally of the carrier in each of these load portions, and such portions then shifted or carried forwardly of the wagon in sequence so as to provide room for the loading of another section from the rear of the wagon, until the complete load is thus obtained. These different operations are in complete and convenient control of the driver at the front of the wagon, and can individually be set in motion or stopped at his will, and act entirely automatically when started, until again stopped by the driver.

The annexed drawings and the following description set forth in detail certain means illustrating my invention, such disclosed means constituting, however, but one of the forms in which the principle of the invention may be shown.

In said annexed drawings:

Figure 1 is a side elevation of my improved hay-loading means in connection with a conventional form of wagon or carrier, the conveyor of a conventional rear-loading hay-loader being suggested;

Figure 2 is a vertical cross-section, taken in the planes indicated by the lines II-II, Figure 1, showing one load portion partially completed, and the packing-arms for uniformly laterally loading the same in the position for pulling or raking the crown of the load section toward the sides of the wagon;

Figure 3 is a view similar to Figure 2 in which the load portion has been completed and packed, and the packing or distributing arms are in their upper or most nearly vertical position, the load portion being ready for shifting or carrying forwardly to provide space for the dumping of another load portion by the ground loader;

Figure 3a is an enlarged fragmentary portion of the top of one of the packing-arms;

Figure 4 is a fragmentary horizontal section, upon an enlarged scale, taken in the plane indicated by the lines IV-IV, Figure 2; and

Figure 5 is a top plan view of the elements shown in Figure 1.

Referring to the annexed drawings in which the same parts are indicated by the same respective ordinals in the several views, I indicate a conventional carrier or wagon frame by the ordinal 1 provided with a running gear including rear and front wheels 2 and 2', respectively, and rear and front axles 2² and 2³, respectively. Secured to a vertical front wall 3 is a platform 4 for the accommodation of the driver who is also in control of the improved hay-loading means hereinafter to be fully described. The wagon frame 1 is mounted on two heavy longitudinal beams A supported upon and rigidly secured to bearing members B mounted upon the axles 2² and 2³, and a plurality of transverse beams C mounted upon the beams A. Upon the foundation comprised of the beams A and C and wagon frame 1 I mount my improved hay-loading means into which the hay is discharged from the rear by the carrier 5 of any conventional form of loading mechanism for automatically transferring the hay from the ground to the wagon. This hay-loading mechanism is ordinarily operated from the running gear of the hay wagon and is shown in the accompanying drawings as operated by the chain 70 engaging the upper sprocket 71 secured to the transverse roller 72, and engaging the lower sprocket 73 secured to the transverse shaft 74, there being secured to the shaft 74 a second sprocket 75 engaging a chain 76 which also engages a sprocket 77 secured to a transverse shaft 43, hereinafter more fully described. The upper rear transverse roller 72 is provided with smooth spring wire teeth 78 and serves to prevent the hay from being pulled back under the conveyor 5 of the ground loader.

The frame 1 comprises carrier frame side members 6 spaced by longitudinal side sills 8 from other transverse side frame members 7 whose inner edges rest upon angle frame members 9 supported upon the inner edges of the side frames 6. An adjustable and flexible flooring or apron 10-11 comprised of transverse relatively jointed members or slats connected by roller links 81 and forming a di-

rect support for the hay is adapted to travel over the angle members 9, as plainly shown in Figure 2. This jointed flooring passes around pulleys 31 secured to the rear of the loader so that, in the position shown in the accompanying drawing, this jointed flooring comprises an upper section 10 and a lower section 11, the latter of which travels over longitudinal metallic bearing strips 12 secured forwardly and rearwardly of the wagon frame and intermediate supported by timbers on transverse beams C which are grooved, as shown by 79, Figure 2, for the accommodation of the bearing strips 12, the actual movement of the jointed flooring around the rollers 31 so as to control the amount of the flooring which shall comprise the upper section 10 at any one time being effected by chains 15 secured beneath the flooring and running over sprockets 30 mounted on the front part of the wagon. The upper floor portion 10 is supported by transverse frame members 16 which are grooved for the accommodation of metal bearing strips 17 over which runs the rollered flooring. The purpose of the adjustable flooring and operating chains just mentioned is to shift a load portion, such as shown in Figure 3, a few feet forwardly from the rear of the wagon and thus provide room at the wagon rear for another load portion to be dumped and properly laterally packed therein. This floor or load adjustment is controlled by the means now to be described. Mounted in the side sills and in the beams A of the wagon frame are three transverse shafts 18, 19 and 20 centrally braced by member 61 secured at their ends to two of the beams C and having bearing portions 62 for said shafts, three sets of sprocket wheels 21, 22 and 23 being secured respectively to said shafts 18, 19 and 20, and adapted to engage the chains 15, the shafts 18, 19 and 20, and the sprockets 21, 22 and 23 being relatively arranged as plainly shown in Figure 1, wherein it will be noted that the shaft 20 is mounted in the beams A and is positioned below and intermediate the shafts 18 and 19 which are mounted in the side sills of the wagon frame, and that the chains 15 run over the top and inner faces of the sprockets 21 and 22 and around and beneath the sprockets 23. A chain 24 passes around a sprocket 25 secured to one rear wheel 2 and also around a clutch section 26 loosely mounted upon the shaft 20. A complementary clutch section 27 secured to the shaft 20 is controlled by a vertical lever 28 positioned adjacent the driver's platform 4 and secured at its lower end to one of a rock shaft 29 which at its other end is secured to the clutch member 27. It is evident from the accompanying drawings and the foregoing description that the driver can control the adjustment of the hay floor proper for shifting the load portions forwardly of the wagon body through the medium of the lever 28 and that

such forward shifting of the load portion can be in an amount desired by the operator.

The several load portions are successively dumped into a housing mounted upon the rear of the wagon. This housing comprises lateral vertical thin metal sections 32 and 33 and a rear section 34, thus affording an upper mouth or opening 35 for the entry of the hay. The capacity of this enclosure is shown in the accompanying drawings to be determined by a built-up front frame or fence section 36 supported by braces 37 upon the wagon frame. When the load is shifted forwardly of the side metal frames 32 and 33 so as no longer to be laterally supported by the latter, it is retained in lateral position from slipping or shifting out of alignment by a pair of longitudinal side ropes or cables 38, plainly shown in Figures 1 and 5.

As the hay is loaded through the entry 35 it is manipulated by automatic packers, so as to secure uniform lateral distribution, by the following means. Secured to a hub portion of one of the wheels 2 is a sprocket wheel 39 engaging with a chain 40 which also engages with a sprocket wheel 41 loosely mounted upon a transverse shaft 43, a hub portion 41' of said sprocket wheel 41 being formed with a clutch portion 42 adapted to cooperate with a cooperating clutch member 42' secured to the transverse shaft 43. At both ends of said shaft 43 are secured bevel gears 44 cooperating respectively with other bevel gears 45 secured to shafts 46. To one end of these shafts 46 are respectively secured sprockets 47 engaging with chains 48 which further engage with sprockets 49 mounted upon crank-shafts 50. The outer ends of the crank-arms 51 are pivotally secured to packer-arms 52 provided at their outer ends with a plurality of packing-fingers 53. The clutch member 42' is secured to a longitudinally extending rock shaft 64 whose front end is secured to a vertically extending lever 65 disposed adjacent the driver's platform 4. It is evident that the operation of the crank-arms 51 and consequently of the packing-fingers 53 is under the control of the operator from the platform 4. Means are provided whereby the packing-arms can automatically find the proper vertical position for the packing operation, whatever the height of the load portion may be, whereby also the dragging or packing effect of the fingers 53 is from the crown and center of the load portion toward the side edges of the wagon and whereby the repeated return or inward movements of the packing-arms 52 from the sides of the wagon toward the top and center of the accumulating load portion shall be in a downward direction so as to avoid interference of the accumulated load with the inward movement of the packing-arms 52. These results are effected by the proper arrangement and coordination of the respective transmission elements, as shown by

the arrows in the accompanying drawings, and by the provision of certain means operating upon and centrally of the packing-arms 52 to give them the respective movements for each cycle of operations which is necessary for these results and which is illustrated in Figures 2 and 3. As shown, the packing-arms 52 are formed with enlarged central portions having elongated slots 52' intersecting which 10 are pins 54 mounted in slide-blocks 55 adapted for vertical reciprocation in elongated slots 56 formed in a pair of spaced vertical side frame members 57 to which the metal housings 32 and 33 are secured. It is evident from 15 the relative disposition of the cranks 51 and the packing-arms 52 and from the direction of movement shown in Figure 2 that the continued rotation of the crank-arms will cause the packing-fingers 53 to pull and distribute 20 the crown of the load portion toward the sides of the wagon, this action continuing until the crank-arms 51 have passed the center of the line of movement. Then the continued rotation of the crank-arms will cause the packing- 25 arms 52 to lift in elongated slots 52' on pins 54, gradually lifting the packing-arms 52 to the position shown in Figure 3 when the crank-arms 51 again pass the center line and the packing-arms 52 will be lowered down 30 to the crown of the load portion which has in the meantime accumulated through the opening 35. The cycle of operations will be repeated until the load portion reaches the dimensions and the shape substantially shown 35 in Figure 3. The pivotal movement of the packing-arms 52 is effected upon rollers 52' mounted upon the pins 54. Within the slots 56 are coiled springs 80 acting upon the blocks 55 and permitting the packing-arms 52 to be 40 raised when the hay has been filled in tightly under them during the finishing of each load portion. In order that accumulated portions of hay between the frame members 57 and the packing-arms 52, when the latter are sub- 45 stantially in the position shown in Figure 3, may not strain or break these arms, I make them of two jointed portions through the medium of a pivotal connection 58, the arm portions being normally held in alignment 50 through the medium of a spring 59 secured at its ends to posts 60 respectively mounted upon two arm portions. The spring 59 is so calibrated that any material strain upon the rear of the arms 52 will cause the arm por- 55 tions to separate at the joint 58 in an amount sufficient to prevent the breaking of the arms. Also, to permit easier unloading, I joint the extreme upper ends of the packing-arms 52, as shown in Figure 3^a. The jointed end 66 60 is secured to the arm proper 52 by a hinge 67 and is retained in alignment by a spring-actuated tooth 68 adapted to engage a strap 69 secured to the arm 52 and formed with a slot 69' with which the tooth 68 is removably 65 engaged.

What I claim is:

1. A hay-loader comprising a wagon including wheels and a frame; a flexible apron support; means for moving said apron forwardly and rearwardly of the frame including transmission elements adapted to be driven by one of said wheels; spreading and packing arms projecting interiorly of said frame; means actuated by the movements of one of said wheels for reciprocating said arms transversely of the frame; and clutch members controlling the operation of said apron-moving means. 70
2. A hay-loader comprising a wagon including wheels and a frame; a flexible apron support; means for moving said apron forwardly and rearwardly of the frame including transmission elements adapted to be driven by one of said wheels; spreading and packing arms projecting interiorly of said frame; means actuated by the movements of one of said wheels for reciprocating said arms transversely of the frame; pivotal mountings for said arms intermediate their free ends and their connections to said reciprocating means; and clutch members controlling the operation of said apron-moving means. 80
3. A hay-loader comprising a wagon including wheels and a frame; a flexible apron support; means for moving said apron forwardly and rearwardly of the frame including transmission elements adapted to be driven by one of said wheels; spreading and packing arms projecting interiorly of said frame; means actuated by the movements of one of said wheels for reciprocating said arms transversely of the frame; pivotal mountings for said arms intermediate their free ends and their connections to said reciprocating means; means providing for the vertical reciprocating of said pivotal mountings; and clutch members controlling the operation of said apron-moving means. 90
4. A packing element for use in hay-loaders comprising, in combination with a supporting frame; an arm extended transversely of the frame and provided with hay-engaging fingers; a vertical support mounted upon the frame and formed with an elongated slot; a pin adapted to be reciprocated in said slot and upon which said arm is pivotally mounted; and means for actuating the outer end of said arm. 100
5. A packing element for use in hay-loaders comprising, in combination with a supporting frame, an arm extended transversely of the frame and provided with hay-engaging fingers; a vertical support mounted upon the frame and formed with an elongated slot; a block adapted to be reciprocated in said slot and provided with a pin upon which said arm is pivotally mounted; and means including a crank for actuating the outer end of said arm. 110
6. A packing element for use in hay-loaders 120
7. A packing element for use in hay-loaders 125
8. A packing element for use in hay-loaders 130

comprising, in combination with a supporting frame; a jointed arm extended transversely of the frame and provided with hay-engaging fingers; elastic means normally holding the jointed portions of said arm in alignment; a vertical support mounted upon the frame and formed with an elongated slot; a pin adapted to be reciprocated in said slot and upon which said arm is pivotally mounted; and means for actuating the outer end of said arm.

7. A packing element for use in hay-loaders comprising, in combination with a supporting frame; an arm extended transversely of the frame and jointed intermediately its ends, said arm being provided at its inner end with hay-engaging fingers; elastic means normally holding the jointed portions of said arm in alignment; a vertical support mounted upon the frame and formed with an elongated slot; a pin adapted to be reciprocated in said slot and upon which said arm is pivotally mounted, the inner finger-portion of said arm also being jointed; releasable means for holding said finger-portion in alignment; and means for actuating the outer end of said arm.

8. A hay-loader comprising running gear; longitudinal main supports mounted upon said running gear; transverse supports mounted upon said main supports; a wagon frame mounted upon said transverse supports; side sills mounted upon said wagon frame; an angle support mounted upon said sills; a flexible apron mounted upon said angle support and movable in box directions over the rear of the wagon frame, the top run of said apron being supported upon said transverse supports; chains incorporated with said apron and movable in both directions over the front of the wagon frame; clutch means connected to said chains; an operator's station mounted upon the front of the wagon frame; an operating lever adjacent said station for actuating said clutch; packing arms mounted transversely of the wagon frame; means for actuating said arms; clutch means connected to said actuating means; a second operating lever adjacent said station for actuating said second clutch; and independent means connecting both of said clutches with the running gear.

9. A hay-loader comprising running gear; longitudinal main supports mounted upon said running gear; a wagon frame supported thereon; a flexible apron mounted upon said angle support and movable in both directions over the rear of the wagon frame; chains incorporated with said apron and movable in both directions over the front of the wagon frame; upper and lower metallic bearing straps for said chains; means for supporting the top and bottom runs of said chains and with which said bearing straps are incorporated; clutch means connected to said chains; an operator's station mounted upon the front

of the wagon frame; an operating lever adjacent said station for actuating said clutch; packing arms mounted transversely of the wagon frame; means for actuating said arms; clutch means connected to said actuating means; a second operating lever adjacent said station for actuating said second clutch; and independent means connecting both of said clutches with the running gear.

10. A hay-loader comprising a wagon including wheels and a frame; a two-part loading-housing mounted upon the rear of said frame and provided with an upper hay-receiving opening; a flexible apron support; means for moving said apron forwardly and rearwardly of the frame including transmission elements adapted to be driven by one of said wheels; spreading and packing arms projecting interiorly of said frame from both sides and extended intermediately the two parts of said loading-housing; means actuated by the movements of one of said wheels for reciprocating said arms transversely of the frame; and clutch members controlling the operation of said apron-moving means.

11. A hay-loader comprising a wagon including wheels and a frame; a loading-housing mounted upon the rear of said frame and provided with an upper hay-receiving opening; a transverse hay-retaining roller mounted adjacent the rear of said housing and provided with hay-engaging teeth; means for rotating said roller to cause said teeth to direct the hay forwardly in said housing, said rotating means including transmission elements adapted to be driven by one of said wheels; a flexible apron support; means for moving said apron forwardly and rearwardly of the frame including transmission elements adapted to be driven by one of said wheels; spreading and packing arms projecting interiorly of said frame; means actuated by the movements of one of said wheels for reciprocating said arms transversely of the frame; and clutch members controlling the operation of said apron-moving means.

12. A packing element for use in hay-loaders comprising, in combination with a supporting frame; an arm extended transversely of the frame and provided at one end with hay-engaging fingers; a vertical support mounted upon the frame and formed with an elongated slot; a pin adapted to be reciprocated in said slot and upon which said arm is pivotally mounted intermediate its ends; a crank for actuating the other end of said arm; and means for automatically operating said crank.

Signed by me this 19th day of April, 1927.
GEORGE ERNEST STROUP.
